In Australia March 18, 1948

8 Claims. (Cl. 197—8)

1

This invention relates to an improved machine for the printing or type-writing of music, and more particularly to improvements in or modifications of a machine of the general character described and illustrated in my United States Patent No. 2,494,192.

That machine has much to recommend it but further research and practical experiments have led to certain improvements or modifications in design, arrangement and construction whereby the production of typewritten music is rendered even more simple, convenient and expeditious as will be hereinafter explained.

My said patent describes a machine comprising a frame-work for supporting various parts, including a key-board, a bank of fingers carrying striking heads, linkage between the key-board and the bank of fingers, an inked ribbon, a vertically arranged platen for supporting the paper to be printed on, and mechanism for traversing the platen horizontally and for raising and lowering the platen while printing or typing operations are in progress. The mechanism for vertical adjustment of the platen includes a shift lever movable between a pair of inclined or curved bars carrying horizontal transverse strips so arranged as to leave a continuous vertical path between their inner ends for movement of the shift lever, and slots between the strips.

One of the primary differences between the original machine and the present machine is that the platen is substantially horizontal and remains stationary during printing or typing operations, and the typing mechanism is movable or traversable over the platen.

Reference will be made to the accompanying drawings which illustrate a preferred practical embodiment of the invention.

In the drawings:

Figure 1 is a perspective view of the embodiment.

Figure 2 is a perspective "under view", in the direction indicated by the arrow II in Figure 1.

Figure 3 is a part sectional elevational view taken on the line III—III of Figure 1.

Figure 4 is a sectional elevational view, similar to a portion of Figure 3, but showing a certain operative phase of a platen portion of the embodiment.

Referring now to Figure 1 the improved machine may comprise a horizontal frame 1 which may be suitably supported upon legs 2 or the like and upon which a platen 3 for mounting or supporting the paper to be printed upon is adapted to be horizontally supported. The paper may

2

be affixed to the supporting platen in any suitable manner, but it is preferred that the platen be capable of relatively slight upward and downward movement with respect to the frame in such a way that when the platen is in the upper position, the paper thereupon is securely held between the platen 3 and transverse retaining strips 4 or bands provided and associated with the frame. In this connection I propose that "flap strips" 6 be hinged along the upper side edges of the platen 3, and be spring influenced in such a manner that when the platen is lowered the "flap strips" 6 rise to enable paper to be inserted or removed, and that when the platen is raised 10 the paper may be firmly retained and secured by the "flap strips" (see Figs. 3 and 4). A spring strip or band 7 adapted to clip on flanges 8 provided on transverse members of the frame 1, may be provided to retain paper which may not extend for the full width of the platen.

A key-board 9 and bank of fingers 11 with associated type heads and linkage mechanism are provided and mounted upon a carriage C so arranged as to be capable of movement or traverse both longitudinally and transversely in a substantially horizontal plane across said supporting platen. The carriage C, keyboard and linkage mechanism may be of any well known commercial typewriter construction; the carriage 25 illustrated being an "Elliott Fisher" apparatus.

For this purpose the aforesaid carriage C is suitably supported upon rollers 12 or the like by a carriage-way 13 extending transversely above the platen. This carriage-way is mounted upon 30 rollers 14 and 14' co-operating with runners 16 provided on the carrying framework in such manner as to permit the carriage-way 13 to be moved longitudinally over the said carriage framework.

40 The carriage-way is also provided with a transversely extending axle 17 upon which are mounted one or more pinions 18 in engagement with a co-operating rack or racks 19 mounted upon the carrying framework in order that controlled longitudinal movement of the carriage-way may be effected in a manner later to be described. The rollers 14 may be mounted upon the transversely extending axle 17.

45 The fingers actuated by the key-board 9 incorporated with the carriage mechanism are each provided with music or other appropriate symbol heads for imprinting corresponding symbols upon paper carried by the platen in underneath relationship with said carriage. The carriage mechanism also includes such operating means

as a back space, space bar, shift key, carriage quick release, for rapid traversing of the carriage, ribbon adjustment, line finder and the like as well known in connection with type-writing and like machines, and similarly a suitable pawl and ratchet device or escapement mechanism is incorporated with the carriage mechanism and adapted to co-operate with a rack 21 or the like upon the supporting carriage-way 13 in such a manner that movement of the carriage across the platen in predetermined spaced steps may be effected manually by the use of the space bar or automatically in timed relationship with the symbol heads actuated by the relative keys in a well-known manner.

The type or symbol heads inscribe the paper through an inked ribbon 20 in the general location indicated by the arrow T, which is convenient for ready inspection of inscribed matter by the operator of the machine.

Normally the carriage will automatically move one space to the right after each note symbol or the like has been written on the paper. It is desirable that manually operable means be provided to temporarily prevent this automatic movement, so as to facilitate the building up of musical chords, arpeggio signs and other musical markings or lines which require longitudinal (or vertical with respect to a manuscript) alignment or continuity. Accordingly, a crank lever 22, with finger piece 22a and predetermined limits of movement, is provided and the spindle 22b thereof is connected in any suitable and simple manner to render the escapement mechanism operative, or non-operative, as desired.

A pair of inclined bars 23, which may if desired be of quadrant configuration, are supported preferably at one end of and attached to the aforementioned carriage-way 13. These inclined bars are provided with horizontal strips 24 along their length so arranged as to leave a continuous vertical path between their inner ends, and slots 24a between the strips. The strips at one side are staggered in relation to the strips at the other side. A shift lever 26 is adapted to be swung through the vertical path between the strips upon the inclined bars, the shift lever also being capable of slight movement to the right and to the left so as to be engaged within a slot formed between an adjacent pair of the horizontal transverse strips 24.

In order to relieve the staggered transverse strips 24, which may be relatively fragile, from being repeatedly engaged by the shift lever 26, two series of pins or studs 27 may project in staggered relationship immediately behind the respective strips to form abutments against which the shift lever can bear when moved into its adjusted positions.

The shift lever 26 may comprise a rod pivoted at its inner end as will be hereinafter described and provided at its outer end with a T-shaped handle 26a or the like in such manner that the shift lever may be turned or twisted as well as being swung in a vertical manner between the inclined bars. Adjacent its inner end, the shift lever rod may be provided with a flexible union to permit of the slight sideward movement to enable the shift lever to be engaged at one or the other side of the vertical path between the inclined bars with the transverse strips.

Accordingly at its inner end, the shift lever is carried by a yoke member 28, which is supported upon a block member 29 pivoted about one end of the transversely extending axle or spindle 17

carried upon the carriage-way 13. The yoke member 28 is supported on the block member 29 by a pivot pin 31 (see Figure 3) to permit slight sideward movement of the shift lever, a spring 5 loaded centering peg 32, with co-operating notch on the underside of the yoke member, being provided to ensure that the shift lever may be normally located in the vertical path between the inclined bars 23. The arrangement is such that a "breakable" coupling is provided between the block member 29 and the transversely extending axle 17 provided with pinions 18 engaging with co-operating racks 19 extending longitudinally upon the carrying framework.

The "breakable" coupling may comprise a flange 34, affixed upon the transversely extending axle 17, provided with holes 36 concentrically formed around the outer face thereof in predetermined positions in such manner that a co-operating pin 37 carried by the block member 29 and actuated in association with a projecting member such as a trigger 38 or the like mounted upon the shift lever 26 is adaptable, by insertion in one of the holes formed upon the flange 34, to cause rotation of the flange and axle as and when the shift lever is swung upwardly or downwardly between the inclined bars. If, however, the pin is withdrawn from engaging contact with the flange, by twisting of the shift lever, and engagement of the trigger 38 with a projection 37a upon the pin 37, no rotative movement will be imparted to the flange or transversely extending axle if the shift lever be then moved upwardly or downwardly between the inclined bars. The pin is normally influenced to engagement with a hole in the flange by means of a spring 39 or the like, and the trigger 38 is normally maintained out of engagement with projection 37a by means of a helical spring 26a operatively connected with the shift lever 26.

Alternate means for appropriate withdrawal from engagement of the pin with the flange may be used; such for example as a flexible cable which may be of the Bowden type, suitably operable from a control on the shift lever.

It is desirable that the end of the pin relative to the flange be of tapered configuration to ensure smooth engagement with the latter.

It will thus be apparent that when the pin 37 is engaged with the flange 34 upon the laterally extending axle 17, and the shift lever 26 is moved upwardly or downwardly between the inclined bars or quadrant, the rotation of the laterally extending axle and its pinions 18 in engagement with the racks 19 upon the carrying framework will cause the carriage-way 13 and carriage C thereon to be moved longitudinally across the paper supporting platen 3.

If the pin is withdrawn and the shift lever moved through the quadrant or inclined bars, no movement of the carriage will take place but this will occur if the pin is again permitted to engage with the flange by twisting or release of the shift lever control.

It is desirable that the holes 36 or co-operating notches upon the flange hereinbefore mentioned be provided in predetermined spaced relationship one to the other, preferably in groups, each comprising three relatively closely spaced holes, and it therefore becomes apparent that predetermined spaced movement of the carriage and carriage-way longitudinally across the platen may be provided by movement of the shift lever between the inclined bars, and by releasing the pin from the flange the shift lever may be moved

to another part of the quadrant scale, as indicated by the horizontal transverse strips thereon, without effecting any movement of the carriage and carriage-way longitudinally across the platen or supporting framework.

A handle 41 upon a suitable portion of the carriage-way 13 is provided for expeditious manual steadyng, or movement, of the carriage-way longitudinally across the platen.

It will thus be apparent that a means such as outlined affords a ready way of changing from stave to stave, for example, when operating the machine in the printing or typewriting of music; and the form of mounting of the carriage mechanism with relation to the paper carrying platen affords a ready way of traversing the former over the latter in operative manipulation of the machine.

The horizontal transverse strips 24 may be arranged in spaced relationship or positioning along the inclined bars or quadrant in much the same manner as has been described in my said patent and may be provided with identification marks or configurations identifying the appropriate strips with the stave line positioning of written music as described in my said previous patent.

It is desirable that spring tension or like means, such as spring band spool 42, be provided to influence the carriage along the carriage-way in a predetermined direction working in association with the carriage ratchet and escapement mechanism. It may be desirable that spring tension or like means be provided to influence or control the longitudinal movement of the carriage and carriage-way across the platen. In this connection I prefer gravity weights, one of which is shown at 43 connected by cord 43a to an appropriate portion of the carriage-way 13.

If so desired, the runners 16 may be on a downward incline towards the front of the machine, rather than horizontal, thereby enabling the carriage-way, and supported components, to be normally influenced forwardly under the influence of gravity.

The means for effecting raising or lowering of the platen 3 will now be described, with particular reference to Figures 2, 3 and 4.

Accordingly, the platen 3 is neatly accommodated between the side pieces 1a and 1b of the frame 1, any upward movement of the platen being limited by the overhanging portion of runners 16, against which the "flap strips" 6 may engage.

A pair of shafts 46 are supported horizontally by, and longitudinally of, the frame 1. A plurality of pairs of arms 47 and 48 are affixed to the shafts 46, the inner ends of the arms 47 and 48 being respectively connected by tongue and slot telescopic connections.

Rollers 49 are rotatably mounted on the upper faces of the arms 47 and 48, and the platen 3 is adapted to be supported upon these rollers 49.

An arm 51 radially outstanding from one of the shafts 46 is connected by link 52 with a minor arm member 53 outstanding from a cross shaft 54, at one end of which is a handle member 56.

The shafts 46 are influenced by springs 57 to normally maintain the arms 47 and 48, and the platen 3 supported thereby, in an upward or raised position.

If the handle member 56 is actuated the cross shaft 54 will be rotated, causing, in effect, the arms 47 and 48 to be moved radially by the shafts

48 and the platen to be lowered against the influence of springs 57 (see Figure 4).

A rod 58 (see Figure 2), the outer end of which is provided with a knurled or like finger piece 59, and the inner end of which is screw threaded, is rotatably supported by a portion of the frame 1, the screw threaded portion being adapted to co-operate with a screw block 61 mounted on the underside of the platen 3. By this means, longitudinal movement or adjustment of the platen 3, supported by rollers 49, upon the machine framework may be conveniently and expeditiously effected.

With due regard for the different characteristics of the machine and the arrangement of component parts thereof, the operation of the machine is substantially on the lines as described in my said previous patent. However, it is considered that the movement of the carriage laterally and longitudinally, over the paper upon a horizontal platen, provides many advantages in operation and practice, amongst which are the ease of operation and the ready visibility of the work being executed.

It will be appreciated that simply by twisting the shift lever, or by other means releasing the pin from the driving flange, the carriage and carriage-way may be moved longitudinally over and away from the work being executed to permit of thorough inspection of the same.

For the purpose of readily inscribing desired lines or marks, such as for example stave lines, upon the paper or the like carried upon the platen, I propose the use of an appropriate number of pens which may be supported in a substantially vertical position, in desired relationship, one to another, from or by the carriage mechanism. I have found that a pen of the ball-point type possesses excellent characteristics for such a purpose, the ink therefrom drying practically instantaneously, thereby obviating smudging, whilst the thickness of line produced may be readily controlled by variation of the pressure of the pen upon the paper.

For convenience, the previous proposal is not illustrated in the drawings, wherein is shown a printing roller 63 having a set of five appropriately spaced circumferential peaks which are adapted to bear against an inking pad (not shown) and which may be caused to bear upon paper, or reproducing stencil, upon the platen by depressing finger piece 64.

Such a device as hereinbefore described is of particular advantage when a master "wax stencil" is being "cut" for subsequent reproduction.

It will also be appreciated that by the use of a single pen-instrument appropriately supported and traversable in relation to the paper a single line or lines may be readily inscribed as desired.

Curves or bow lines may be readily inscribed by simultaneous lateral and longitudinal movement of the carriage which carries the pen, over the paper. In the drawings, a single roller wheel 66 is shown supported for inscribing single lines; it may be brought into engagement with the paper or stencil upon the platen by depressing finger piece 67.

Whilst the foregoing description relates to an embodiment of the machine which at present is preferred, it is to be understood that it is susceptible to various modifications, refinements and/or additions without departure from the true spirit and scope of the invention, as defined by the appended claims.

Having now described my invention, what I

claim as new and desire to secure by Letters Patent is:

1. An improved music writing machine comprising a stationary platen for supporting paper to be written upon, type-writing mechanism, manually operable means for effecting movement of said mechanism over the paper supporting surface of the platen, such manually operable means comprising a scale or indicator device having upstanding laterally spaced bars providing a continuous pathway between them, the adjacent or inner faces of the bars having staggered horizontal slots spaced apart in conformity with the lines and the intervening spaces of a musical stave, a lever adapted to be moved with a swinging motion lengthwise through said pathway and having capacity for limited sidewise movement into any of said slots, and operative connections for translating said swinging motion of the lever into movement of said mechanism longitudinally over the said platen.

2. A music writing machine, comprising a platen stationarily mounted in a substantially horizontal plane for supporting paper to be written upon, typewriting mechanism, supporting means for said mechanism for enabling it to be moved both longitudinally and transversely in relation to the stationary platen, and manually operable means for adjusting said mechanism into predetermined positions longitudinally over the platen, said manually operable means including a scale or indicator device having upstanding laterally spaced bars providing a continuous pathway between them, the adjacent or inner faces of the bars having staggered horizontal slots spaced apart in conformity with the lines and the intervening spaces of a musical stave, a lever adapted to be moved with a swinging motion lengthwise through said pathway and having capacity for limited sidewise movement into any of said slots, and operative connections for translating said swinging motion of the lever into substantially longitudinal and horizontal movement of said mechanism over the said platen.

3. A music writing machine, comprising a platen stationarily mounted in a substantially horizontal plane for supporting paper to be written upon, typewriting mechanism, supporting means for said mechanism for enabling it to be moved longitudinally and transversely in relation to the stationary platen, and manually operable means for adjusting said mechanism into predetermined positions longitudinally over the platen, the supporting means for said mechanism comprising a framework having along its opposite sides longitudinally extending, substantially horizontal runners, a carriage-way member, rollers on said member for tracking along said runners, an axle extending transversely of said carriage-way member, said axle being provided with toothed pinions, toothed racks on said framework engaged by the pinions, manually operable means, including a swingable lever for imparting rotation to said axle to thereby move the carriage-way member lengthwise with respect to the framework and the platen supported thereby, a disengageable coupling between said swingable lever and said axle whereby swinging motion of the lever may be effected if desired without imparting rotative movement to the said axle, said disengageable coupling comprising a flange affixed upon the said axle, the flange being provided with holes concentrically formed around the outer face thereof in predetermined positions, and a cooperative pin associated with the lever, 75

which pin is normally influenced into engagement with one of the holes in the said flange and is adapted to be withdrawn from said hole for the purpose of disengaging the coupling when desired.

4. A music writing machine, comprising a platen stationarily mounted in a substantially horizontal plane for supporting paper to be written upon, typewriting mechanism, supporting means for said mechanism for enabling it to be moved longitudinally and transversely in relation to the stationary platen, and manually operable means for adjusting said mechanism into predetermined positions longitudinally over the platen, the supporting means for said mechanism comprising a framework having along its opposite sides longitudinally extending, substantially horizontal runners, a carriage-way member, rollers on said member for tracking along said runners, an axle extending transversely of said carriage-way member, said axle being provided with toothed pinions, toothed racks on said framework engaged by the pinions, manually operable means, including a swingable lever for imparting rotation to said axle to thereby move the carriage-way member lengthwise with respect to the framework and the platen supported thereby, a disengageable coupling between said swingable lever and said axle whereby swinging motion of the lever may be effected if desired without imparting rotative movement to the said axle, said disengageable coupling comprising a flange affixed upon the said axle, the flange being provided with holes concentrically formed around the outer face thereof in predetermined positions, and a cooperative pin associated with the lever, which pin is normally influenced into engagement with one of the holes in the said flange and is adapted to be withdrawn from said hole for the purpose of disengaging the coupling when desired, said cooperative pin having a projection thereon and said lever having a projecting member thereon in such relation to the projection upon the pin that axial twisting of the lever will cause the pin to be withdrawn from the hole in the flange with which it is normally engaged.

5. A music writing machine, comprising a platen stationarily mounted in a substantially horizontal plane for supporting paper to be written upon, typewriting mechanism, supporting means for said mechanism for enabling it to be moved longitudinally and transversely in relation to the stationary platen, and manually operable means for adjusting said mechanism into predetermined positions longitudinally over the platen, the supporting means for said mechanism comprising a framework having along its opposite sides longitudinally extending, substantially horizontal runners, a carriage-way member, rollers on said member for tracking along said runners, an axle extending transversely of said carriage-way member, said axle being provided with toothed pinions, toothed racks on said framework engaged by the pinions, manually operable means, including a swingable lever for imparting rotation to said axle to thereby move the carriage-way member lengthwise with respect to the framework and the platen supported thereby, a disengageable coupling between said swingable lever and said axle whereby swinging motion of the lever may be effected if desired without imparting rotative movement to the said axle, said disengageable coupling comprising a flange affixed upon the said axle, the flange being provided with holes concentrically formed around

the outer face thereof in predetermined positions, and a cooperative pin associated with the lever, which pin is normally influenced into engagement with one of the holes in the said flange and is adapted to be withdrawn from said hole for the purpose of disengaging the coupling when desired, said cooperative pin having a projection thereon and said lever having a projecting member thereon in such relation to the projection upon the pin that axial twisting of the lever will cause the pin to be withdrawn from the hole in the flange with which it is normally engaged, said holes on the flange being provided in predetermined spaced groups, each group comprising three relatively closely spaced holes.

6. A music writing machine, comprising a platen stationarily mounted in a substantially horizontal plane for supporting paper to be written upon, typewriting mechanism, supporting means for said mechanism for enabling it to be moved longitudinally and transversely in relation to the stationary platen, and manually operable means for adjusting said mechanism into predetermined positions longitudinally over the platen, the supporting means for said mechanism comprising a framework having along its opposite sides longitudinally extending, substantially horizontal runners, a carriage-way member, rollers on said member for tracking along said runners, an axle extending transversely of said carriage-way member, said axle being provided with toothed pinions, toothed racks on said framework engaged by the pinions, manually operable means, including a swingable lever for imparting rotation to said axle to thereby move the carriage-way member lengthwise with respect to the framework and the platen supported thereby, a supporting frame for the platen, the platen being capable of relatively slight upward and downward movement relative to the said supporting frame, a strip connected by a hinge to an upper edge of the platen and resilient means whereby when the platen is lowered the strip opens about the hinge to allow paper to be inserted or removed, and when the platen is raised the strip closes in order to retain the paper upon the platen.

7. A music writing machine, comprising a platen stationarily mounted in a substantially horizontal plane for supporting paper to be written upon, typewriting mechanism, supporting means for said mechanism for enabling it to be moved longitudinally and transversely in relation to the stationary platen, and manually operable means for adjusting said mechanism into predetermined positions longitudinally over the platen, the supporting means for said mechanism comprising a framework having along its opposite sides longitudinally extending, substantially horizontal runners, a carriage-way member, rollers on said member for tracking along said runners, an axle extending transversely of said carriage-way member, said axle being provided with toothed pinions, toothed racks on said framework engaged by the pinions, manually operable

means, including a swingable lever for imparting rotation to said axle to thereby move the carriage-way member lengthwise with respect to the framework and the platen supported thereby, a supporting frame for the platen, and means for raising and lowering of the platen, said means comprising a pair of shafts supported horizontally and longitudinally of the supporting frame, a plurality of pairs of arms affixed to the shafts at their outer ends, the inner ends of related arms being connected together in slotted telescopic connection, rollers carried by said arms on the upper face thereof whereupon the platen is adapted to be supported, spring means to normally influence said arms and platen into a raised position, connecting linkage actuation of which causes the arms and platen carried thereby to be lowered against the influence of said spring means, and a handle member for actuating said connecting linkage.

8. A music writing machine, comprising a platen stationarily mounted in a substantially horizontal plane for supporting paper to be written upon, typewriting mechanism, supporting means for said mechanism for enabling it to be moved longitudinally and transversely in relation to the stationary platen, and manually operable means for adjusting said mechanism into predetermined positions longitudinally over the platen, the supporting means for said mechanism comprising a framework having along its opposite sides longitudinally extending, substantially horizontal runners, a carriage-way member, rollers on said member for tracking along said runners, an axle extending transversely of said carriage-way member, said axle being provided with toothed pinions, toothed racks on said framework engaged by the pinions, manually operable means, including a swingable lever for imparting rotation to said axle to thereby move the carriage-way member lengthwise with respect to the framework and the platen supported thereby, and means provided for longitudinal movement or adjustment of the platen relative to the supporting framework and carriage-way member and comprising a rod supported by a portion of the framework, a knurled finger piece at the outer end of the rod, the inner end of the rod having a screw thread, and a screw-block mounted on the under-side of the platen for cooperation with said screw thread.
